UNITED STATES PATENT OFFICE.

WILLIAM H. GRINDLEY, OF CONGLETON, ENGLAND, ASSIGNOR TO WILLIAM S. PITCAIRN, OF NEW YORK, N. Y.

DESIGN FOR A COVERED DISH.

SPECIFICATION forming part of Design No. 26,460, dated December 29, 1896.

Application filed November 13, 1896. Serial No. 612,027. Term of patent 3½ years.

To all whom it may concern:

Be it known that I, WILLIAM H. GRINDLEY, a citizen of Great Britain, residing at Congleton, in the county of Chester, England, have
5 invented a certain new and ornamental Design for a Covered Dish; and I do hereby declare the following to be a full, clear, and exact description of the same, reference being had to the accompanying drawings, forming
10 a part hereof.

In the accompanying drawings, which form part of this specification, Figure 1 is a top plan view of the covered dish embodying my design. Fig. 2 is a side view, and Fig. 3 an end
15 view, of the same.

The following are the leading features of my design: The upper edge of the dish A and its cover B are in the form of an octagon, slightly elongated, (owing to the fact that two
20 of the opposite sides are larger than the other six) and the sides of which are slightly concave. Along the cover is a depressed line near the edge and parallel therewith. On the cover, at each interior angle of the polygon,
25 is embossed an ornamentation *a*, consisting of a trifoliate figure, from the base of which on each side springs an inwardly-curved scroll terminating in a long and short branch.

The cover is elevated at the center and is
30 provided with a handle. Near the handle and

surrounding the same are embossed four ornamental figures, two of them being the same, *a*, as are placed at the angles of the cover. The other two, *b*, which alternate with these, consist each of a scroll terminating in three 35 branches, two curving in the direction of the scroll and the third reversed.

The body of the dish is composed of eight concave panels narrowing toward the bottom, toward which they retreat backward and 40 downward to form feet separated by arches. The handles are placed at opposite ends of the body. At each change of direction and near the outside upper edge of the dish-body is placed the embossed ornamentation *a*, except 45 that one-half of the ornamentation is removed on the two end panels to make room for the handles. At each foot is embossed a trifoliate ornamentation *c*, resembling a fleur-de-lis pointing upward. 50

What I claim is—

The design for dishes substantially as shown and described.

In testimony whereof I have signed this specification in the presence of two subscribing witnesses. 55

WILLIAM H. GRINDLEY.
